UNITED STATES PATENT OFFICE.

MARCEL J. WIART, OF OGDEN, UTAH.

PRIMARY CLASSIFICATION PLATE.

Application filed March 30, 1923. Serial No. 628,932.

To all whom it may concern:

Be it known that MARCEL J. WIART, a citizen of the United States, residing at Ogden, in the county of Weber and State of Utah, has invented certain new and useful Improvements in Primary Classification Plates, of which the following is a specification.

This invention relates to a primary classification plate and it consists in the novel features hereinafter described and claimed.

An object of the invention is to provide a classification plate especially adapted to be used in conjunction with the Henry system of fixing or determining the fractional values of finger prints. In accord with the Henry system the prints are associated in groups having different fractional values or fractions composed of different numerators and different denominators. The first group is represented by the fraction 16/16. The second by the fraction 8/8. The third by the fraction 4/4. The fourth by the fraction 2/2 and the fifth by the fraction 1/1. Adding the respective numerators and denominators together the fraction 31/31 is given. To each term of this fraction one is added arbitrarily in order to provide a fraction which is easy to handle and making the fraction 32/32.

In the accompanying drawing:—

Figure 1 is a side elevation of the plate viewing one side surface thereof.

Figure 2 is a similar view of the plate viewing the opposite side surface thereof.

Figure 3 is an elevational view of a finger print card which is used in conjunction with the plate.

The finger print apparatus comprises a card C having finger print impressions thereon and arranged in rows. One row including the prints of the fingers of the right hand and the other row including the prints of the fingers of the left hand. These prints are distinguished from each other by proper legends as for instance 1 right hand thumb. 2 left forefinger. 3 right middle finger. 4 right ring finger. 5 right middle finger. 6 left thumb. 7 left forefinger. 8

left middle finger. 9 left ring finger. 10 50 left little finger.

The apparatus also includes a plate A provided with openings B the said openings adapted to be moved into register with the finger print impressions upon the card. The 55 openings are arranged in rows and the openings in one row are in staggered relation with respect to the openings in the adjacent row.

The plate A is provided at one side surface and adjacent the openings B with legends as follows. Numerator value 16. Numerator value 8. Numerator value 4. Numerator value 2. Numerator value 1. At the same side surface and adjacent these 65 respective openings also appear the following legend. Right index finger, right ring finger, left thumb, left middle finger, left little finger. At the opposite side surface the plate is provided adjacent the respective openings with the following legends: Denominator value 16. Denominator value 8. Denominator value 4. Denominator value 2. Denominator value 1, and adjacent the respective openings with the additional legends as follows: Right thumb, 70 right middle finger, right little finger, left index finger, left ring finger. When the plate is used upon the card it is turned 75 over away from the user and along its median longitudinal axis so as to bring the various openings in the plate into register with the corresponding prints upon the card C and in order that the numerators and denominators of the fractional numbers which represent the several prints may be accurately determined.

From the foregoing it will be seen that I have provided a primary classification plate and apparatus by the use of which the art of classifying can be learned with minimum expenditure of time, a primary classification plate which is durable, simple to make and use and which will insure accuracy of results with ordinary care. 90 95

What I claim as new and desire to secure by Letters Patent is:—

1. A finger print apparatus comprising a

card having finger print impressions thereon and arranged in horizontal rows and a plate adapted to be positioned upon the card and having openings adapted to be moved into register with the finger print impressions upon the card.

2. A finger print apparatus comprising a card having finger print impressions thereon and arranged in rows and a plate having

openings therein and adapted to be brought into register with the finger print impressions upon the card the said openings being arranged in rows and the openings in one row being in staggered relation with respect to the openings in the adjacent row.

In testimony whereof I affix my signature.

MARCEL J. WIART.
